CLAIM

The ornamental design for a LED lamp, as shown and described.

DESCRIPTION

FIG. 1 is a front perspective view of a LED lamp according to an embodiment;

FIG. 2 is an enlarged front view of the LED lamp of FIG. 1;
FIG. 3 is an enlarged rear view of the LED lamp of FIG. 1;
FIG. 4 is a left side view of the LED lamp of FIG. 1;
FIG. 5 is a right side view of the LED lamp of FIG. 1;
FIG. 6 is a top view of the LED lamp of FIG. 1;
FIG. 7 is a bottom view of the LED lamp of FIG. 1;
FIG. 8 is a front perspective view of the LED lamp shown in use and with an enlarged portion; and,
FIG. 9 is a front perspective view of the LED lamp of FIG. 1 shown in use with an exemplary suspension type application and including end caps with the light emitting part in diagonal line.

The radiating broken lines shown in FIG. 8 and the diagonal broken lines shown in FIG. 9 illustrate illumination and form no part of the claimed design.

The broken lines in the drawings illustrating environmental structures form no part of the claimed design.
